UNITED STATES PATENT OFFICE.

PHILIP A. FISCHER, OF NEW YORK, N. Y.

DRINKING CUP.

Application filed November 18, 1924. Serial No. 750,572.

To all whom it may concern:

Be it known that I, PHILIP A. FISCHER, a citizen of the United States, residing at New York, in the county of New York and State of New York, have invented certain new and useful Improvements in Drinking Cups, of which the following is a specification.

This invention is a foldable paper drinking cup, particularly designed for pouring the liquid contents of the cup from the central part of a pouring extension, without the possibility of spilling the contents over the edge of the pouring extension, even though the cup be subjected to considerable shaking. The pouring extension extends from the body portion of the cup, and narrows to a pouring edge of substantial width. Flaps extend along one edge of the pouring extension, being preferably integral therewith. These flaps form liquid confining pockets which are fairly deep toward the side edges of the cup, but which decrease in depth toward the discharge or pouring edge, so that the liquid is guided to such discharge edge, and spilling of liquid over the outer edges of the pouring extension is effectively prevented.

The pouring or discharge edge of the pouring extension is re-enforced or stiffened by pasting one or more re-enforcing members thereto. The ends of the flaps may be pasted to the pouring edge to form such re-enforcement.

The flaps extend along the lateral edges of the pouring extension and join at one end with the body of the cup through a fold which forms a spring hinge which tends to push the back of the cup away from the front, thereby initiating the opening of the cup, in a manner somewhat similar to that shown in my prior Patent No. 1,373,182, dated March 29, 1921, whereby the cup may be completely opened by pressing the side edges inwardly.

The cup in my prior patent has a restricted, funnel-like pouring extension with a closed top. According to the present invention, the pouring extension has an open top, whereby a more rapid discharge of the contents is attained, and the pouring edge may be taken into the mouth like the rim of an ordinary drinking glass.

In the drawings, illustrating certain embodiments of the invention,

Fig. 1 is a front view of the cup,

Fig. 2 is a central cross section of the cup in open position,

Fig. 3 is a central cross section through the upper part of the cup in closed position,

Figs. 4, 5 and 6 are views respectively similar to Figs. 1, 2 and 3, of a modification,

Figs. 7 and 8 are views respectively similar to Figs. 1 and 2 of another modification.

Fig. 9 is a front view of a third modification,

Fig. 10 is a central cross section of the cup in Fig. 9 in open position,

Fig. 11 is a view of the cup in Fig. 9 at one stage in assembling it, and

Fig. 12 is a perspective view of the cup of Figs. 1 or 4 in pouring position.

Referring now to the accompanying drawing, in which similar reference characters indicate similar parts, the cup comprises a front portion 1, a back portion 2, and the usual bottom sealing flap 3. The back portion 2 is extended as at 4 to form a pouring extension, such extension narrowing to a pouring edge 5, which may be rounded or straight.

Arranged along the edges of the pouring extension 4 is a pair of flaps 6 and 7 which are preferably integral therewith. The outer ends of these flaps are connected to the front portion 1 of the cup by a triangular piece 8, the line of junction of the two being indicated at 9. The flap 6 or 7, as the case may be, the triangular piece 8, and the front piece 1 are all preferably integral, whereby a spring hinge is formed, the pivot line of which is the line 9, which, by reason of the deformation of the paper, due to the fold, tends to push the front portion 1 of the cup away from the back portion 2 and so initiate the opening of the cup. A further pressure against the two sides of the cup will cause the cup to open completely as in Fig. 2 thereby providing a cup which is opened almost automatically and without the necessity of using the fingernail or similar means for opening the cup.

The flaps 6 and 7 extend toward each other and extend inwardly of the cup to form liquid confining pockets P. The adjacent ends of the flaps 6 and 7 are preferably overlapped as at 10 and are pasted to each other and to the pouring edge of the cup.

Referring to Fig. 1, those portions of the flaps 6 and 7 above the line A, A, are

2
pasted to the outer part of the extension 4, thereby strongly reinforcing such pouring edge. The fact that the flaps 6 and 7 are thus pasted, cause the liquid confining pockets P to grow shallower until, at the line A—A, the pockets vanish and the liquid flows over the discharge edge 5.

The form of the invention shown in Figs. 4, 5 and 6 is generally similar to the form 10 shown in Figs. 1 and 2, the hinge arrangement being slightly different. In Figs. 1 and 2, the ends of the flaps 6 and 7 fold under the front 1 of the cup. In Figs. 4 and 5, they fold over the front 1 of the cup. Referring to Fig. 5, connecting one end of the flap 6 or 7 with the front 1 of the cup, are members 15 and 15' which have three lines of fold indicated at 16, 17 and 18. When the cup is closed, the hinge 15 folds along 15 lines 16, 17 and 18 underneath the end of the flap, while the end of the flap overlaps the front of the cup as indicated at 19.

Referring now to Fig. 7, the pouring edge 25 of the cup indicated at 20 is reinforced by a flap 21 preferably integral with the pouring extension 4, and folded onto the front extension 4 and pasted thereto. The flaps 6', 7', are hinged at their respective outer ends to the front portion 1 of the cup and 30 extend toward the pouring edge 20, gradually decreasing in height toward that edge thereby to form liquid confining pockets P for guiding the liquid to such pouring edge.

Flaps 6' and 7' are connected to the front 35 of the cup by a hinge member 22 foldable along the lines 23 and 24 forming a spring hinge somewhat similar to that shown in Figs. 4 and 5.

Referring now to the modifications shown 40 in Figs. 9, 10, and 11, the flaps 25 and 26 are connected to the front 1 by spring hinges 27 of the type shown in Fig. 8. These flaps have extensions 25' and 26' respectively, of the form shown in Fig. 11. In 45 order to assemble the cup, one flap, such as 26' is folded inwardly along the line 28, then the other flap is folded over it along the line 29 and then both are bent back on the line 30 carrying with them the triangular piece 31, and pasted to the back of the 50 cup as shown in Fig. 10. The line 30 forms the pouring edge of the cup.

Referring particularly to Fig. 12, it will be seen that the pouring pockets P are fairly 55 deep toward the outer edges of the cup and gradually decrease in depth towards the pouring edge 5, whereby the liquid contents of the cup is prevented from splashing or spilling from the edge of the cup and is 60 guided accurately to such pouring edge. The pouring edge is reinforced and stiffened as shown in the several figures, thereby keeping it from bending, and keeping it in a more or less straight horizontal line, 65 whereby it will fit much more readily in

the mouth of the user, than if the sides of the cup converge to a point rather than to a pouring edge of substantial width, as is the case with applicant's invention.

While I have illustrated certain preferred forms of my invention in some detail, it should be understood that the invention may be carried out in other ways as expressed within the scope of the appended claims.

1. A folding drinking cup comprising a body portion, an open-topped pouring extension, flaps along the sides of the pouring extension forming liquid confining pockets for guiding liquid toward the discharge edge of the pouring extension, the adjacent ends of said flaps being secured to the pouring extension near its discharge edge for reinforcing that edge.

2. A folding drinking cup comprising a body portion, an open-topped pouring extension, upwardly extending flaps along the sides of the pouring extension forming liquid confining pockets for guiding liquid toward the discharge edge of the pouring extension, the adjacent ends of said flaps being secured to each other and to the pouring extension near its discharge edge for reinforcing that edge.

3. A folding drinking cup comprising a body portion, an open-topped pouring extension, and means forming liquid confining pockets decreasing in depth toward the discharge end of the pouring extension for guiding liquid toward the outer central part 100 of such extension.

4. A folding drinking cup comprising a body portion, an open-topped pouring extension narrowing to a central discharge edge of substantial width, means for reinforcing said discharge edge, and means for forming liquid confining pockets for guiding liquid to said discharge edge.

5. A folding drinking cup comprising front and back body-forming portions, an open topped pouring extension narrowing to a discharge edge, and flaps extending along the lateral edges of the pouring extension forming liquid confining pockets for guiding the liquid to the discharge edge, the flaps being connected to front of the body portion by folds forming spring hinges for facilitating the opening of the cup.

6. A folding drinking cup comprising front and back body-forming portions, an open topped pouring extension narrowing to a discharge edge, flaps extending along the lateral edges of the pouring extension forming liquid confining pockets for guiding the liquid to the discharge edge, the flaps being connected to the front of the body portion by folds forming spring hinges for facilitating the opening of the cup, and means for re-enforcing the discharge edge of the pouring extension.

7. A folding drinking cup comprising front and back body-forming portions, an open topped pouring extension narrowing to a discharge edge, and flaps extending along the lateral edges of the pouring extension forming liquid confining pockets for guiding the liquid to the discharge edge, 20 the flaps being connected to the front of the body portion by folds forming spring hinges for facilitating the opening of the cup, the adjacent ends of the flaps being pasted to the pouring extension near the discharge edge for re-enforcing it.

8. A folding drinking cup comprising front and back body-forming portions, an

open topped pouring extension narrowing to a discharge edge, and flaps extending along the lateral edges of the pouring extension forming liquid confining pockets for guiding the liquid to the discharge edge, 20 the flaps being connected to the front of the body portion by folds forming spring hinges for facilitating the opening of the cup, the adjacent ends of the flaps being pasted to the discharge edge, for re-enforcing it.

In testimony whereof I affix my signature.

PHILIP A. FISCHER.
